THE NORRIS PETERS CO., PHOTO-LITHO., WASHINGTON, D. C.

UNITED STATES PATENT OFFICE.

FRANK L. WESTBROOK, OF FISH, GEORGIA.

PLOW.

1,230,963.

Specification of Letters Patent. Patented June 26, 1917.

Application filed August 28, 1916. Serial No. 117,282.

To all whom it may concern:

Be it known that I, FRANK L. WESTBROOK, a citizen of the United States, residing at Fish, in the county of Polk and State of Georgia, have invented certain new and useful Improvements in Plows, of which the following is a specification.

This invention relates to turning plows and seeks primarily to provide a point which may be readily adjusted to compensate for wear and which may be used for a long time efficiently. The invention also seeks to provide a point which is reversible so that it may be used in the field without any appreciable loss of time. The invention also seeks to provide novel means for adjusting the landside and the frog relative to the point so as to obtain the desired penetration of the point, and also to provide an improved share.

The invention is illustrated in the accompanying drawings and consists in certain novel features which will be first fully described and then more particularly pointed out in the claims following the description.

In the drawings:

Figure 1 is a perspective view of a plow embodying my present improvements;

Fig. 2 is a side elevation of the same;

Fig. 3 is a plan view with parts in section;

Fig. 4 is an elevation with parts in section and looking at the side opposite that shown in Fig. 2;

Fig. 5 is a rear elevation with parts in section;

Fig. 6 is a detail perspective view of the point;

Fig. 7 is a detail perspective view of the share.

The beam 1 and the handles 2 may be of any desired formation, the handles being connected with the beam by braces 3 as shown and as is now ordinarily done. The rear end of the beam is turned downwardly to form a standard 4 and is secured to the frog 5 by a bolt 6 inserted through the standard and a longitudinal slot 7 in the frog near the upper rear corner of the same, the lower end of the standard being secured to the frog by a bolt 8 which firmly secures the parts together but may operate as a pivot to permit relative adjustment of the standard and beam and the frog. The landside 9 is pivotally attached at its front end, as

shown at 10, to the side of the frog near the lower edge thereof and the frog will preferably be constructed with a concave seat to receive the front end of the landside, as shown in Fig. 2. The landside is provided with a heel or flange 11 at its lower edge which projects under the lower edge of the frog and is wider at its rear end than at its front end. This construction gives the landside a firm bearing upon the ground in the bottom of the furrow and also permits the landside to be so adjusted that it will run on the bottom of the furrow notwithstanding the angle to which the point may be adjusted. Near its rear end the landside carries a bolt 12 which passes through a vertical slot 13 in the frog so that the vertical adjustment of the rear end of the landside may be accommodated and the landside secured firmly in any position in which it may be set. To further aid in holding the landside in its adjusted position, lugs or corrugations 14 are provided on the opposed adjacent faces of the landside and of the frog so that when the bolt 12 is tightened the corrugations or lugs are firmly engaged and prevent relative vertical movement of the frog and landside. The bolt 12 also serves to secure the lower ends of the handles to the frog.

The front edge or corner of the frog is formed on a regular curve which may be of any desired radius according to the size and weight of the plow. The point 15 consists of a bar of tempered steel which is bent from end to end on a curve corresponding exactly with the curvature of the front edge of the frog so that the point will seat smoothly and firmly against the frog and have an extended support or bearing thereon. The point is provided with a plurality of openings 16 through which suitable securing bolts 17 may be passed, the openings being countersunk so that the heads of the bolts will lie flush with the forward or outer surface of the bar constituting the point. The said bolts 17 pass through slots 18 in a rib 19 formed on the side of the frog along the front edge of the same, as clearly shown in Fig. 2, this arrangement accommodating any slight irregularity which may occur in the spacing of the openings 16 and also permitting a short worn bar to be firmly secured to the frog. The bar 15 is twisted slightly toward its

opposite ends so that the upper end of the bar, when the same is in position, will project forwardly and operate as a shin, as indicated at 20, while the extremities of the 5 bar are turned slightly outwardly or away from the center of curvature of the bar, as shown at 21, so as to provide spurs or points which will readily penetrate the ground. Should one cutting end or point of the bar 10 become worn or dull through long continued use, the bar may be removed and replaced after being inverted so that the unused end which was formerly uppermost will become the working end and will penetrate the 15 ground. The period during which the plow cannot be used will, therefore, be of no consequence inasmuch as the point may be inverted by the user in the field and the securing bolts are accessible inasmuch as they 20 are inserted through the lateral rib 19 and are thereby spaced from the side of the frog. As the bar becomes shorter through protracted use and frequent sharpening it may be set lower upon the concave curved front 25 edge of the frog and will seat firmly against the same, the turned point or spur 21 being received in sockets or corrugations 22 in the front side of the frog so that the point will seat firmly against the frog and a short bar 30 will efficiently resist the thrust upon the plow when it is in use. Should the bar become very short, a short piece of metal or an old worn out point may be secured upon the frog above the point which is in use so 35 that the front of the frog may be protected from wear and the slots 18 cannot clog up. The construction permits the use of a bar until nearly all of it is worn away inasmuch as it may be used until the upper opening 40 16 in the bar will pass below the lower end of the lower slot 18 in the rib 19, as will be readily understood.

The moldboard 23 is secured to the front side of the frog and fits against the edge of 45 the point 15 so as to be flush therewith and the share 24 is secured to the lower end of the frog and connected with the lower edge of the moldboard by suitable bolts and attaching plates, as will be readily understood. The share is symmetrical so that it 50 may be reversed to accommodate for wear and its longitudinal edges are beveled, as shown at 25, so that the lower edge will readily enter the ground while the upper edge will fit over the lower beveled edge of the moldboard and bring the front faces of the share and the moldboard in the same plane, thereby permitting the dirt to pass 55 readily over the share and the moldboard 60 without lodging in the joint between them. The end of the share fits closely against the side edge of the point, as clearly shown in the drawings and as will be readily understood.

65 As previously stated, the point may be

adjusted end-wise upon the frog and this adjustment permits me to set the point so that it will penetrate the ground to any desired depth. It is necessary, of course, to adjust the landside and the beam to correspond to the adjustment of the point, and the slot 7 in the upper portion of the frog permits the needed adjustment of the beam relative to the frog. To aid in holding the beam and the frog in their proper relative 70 positions, lugs, corrugations or projections 75 26 are provided upon the opposed faces of the standard and the frog. A locking key or wedge 27 is also provided, the front face of the said key or wedge being preferably 80 straight and being provided with transverse grooves or notches 28 adapted to be engaged by the upper rear edge of the moldboard supporting member of the frog and the rear side of the wedge or key being curved so 85 that it may fit closely against the front curved side of the standard, as shown clearly in Fig. 4. This locking key or wedge is carried by the upper end of a bar or link 29 which has its lower end secured to the 90 landside 9 near the rear end thereof, the upper end of said bar or link being provided with a plurality of openings 30 through any one of which an attaching bolt may be inserted into the wedge or key so that the 95 working length of the bar or link may be varied to suit the adjustment which may be given the landside and the wedge. When a change in the relative position of the frog and the standard or beam is necessary or 100 desired the bolt 6 is loosened and the standard or beam then moved pivotally upon the bolt 8 until it reaches the desired position after which the wedge 27 is adjusted so that it will fit snugly between the front portion 105 of the frog and the front side of the beam or standard. The bolt 6 is then tightened and the parts will be held firmly in the position in which they have been set.

It will be readily seen from the foregoing 110 description, taken in connection with the accompanying drawings, that I have provided a very simple structure by which the efficiency of a turning plow will be enhanced. The point, owing to its reversibility and its symmetrical form and the fact that it is formed on a simple regular curve so that it has a long bearing upon the front side of the frog, may be used for a very long time without requiring the provision of a 115 new point and the slight twist given the extremities of the point not only permit it to readily enter the ground to the desired depth but also aid in holding it in its proper position when it has become worn as the 120 upper end of the point in use will engage a socket in the front face of the frog and thereby serve as a brace to prevent the point slipping up on the frog when the 125 plow happens to strike a large rock or other 130

obstruction. By properly forming the bevels on the longitudinal edges of the share and fitting the securing bolts in slots the share may be adjusted forwardly so as to 5 compensate for wear and, consequently, may be used for a long time without requiring the provision of a new share.

Having thus described the invention, what is claimed as new is:

10 1. A plow provided with a point consisting of a bar forming a simple curve from end to end, its front face being concave and its rear face convex and its extremities being turned rearwardly to project from its 15 rear convex face, and the edges of the bar being parallel throughout the length of the same.

2. In a plow, the combination of a frog having its front edge forming a simple 20 curve from top to bottom, a point consisting of a bar seating from end to end directly on the front edge of the frog and having side edges parallel throughout their length, a moldboard secured at one end upon 25 the frog against a side edge of the point and flush with the front face of the same, and a share secured at one end to the frog against the side edge of the point below the moldboard and flush with the point and the 30 moldboard.

3. In a plow, the combination of a frog having its front edge forming a regular curve and provided on one side at said edge with a rib following said curve, a point 35 consisting of a bar curved from end to end and seating directly upon the front curved edge of the frog, and securing bolts inserted through said bar and through the said rib on the frog.

40 4. In a plow, the combination of a frog having its front edge forming a regular curve, a point consisting of a bar curved from end to end to seat upon the said front edge of the frog, a standard pivotally 45 secured at its lower end to the side of the frog, means for adjustably securing the upper portion of the standard to the frog, and an adjustable key disposed between the

front side of the standard and the rear side of the frog.

5. In a plow, the combination of a frog, a point consisting of a bar seating from end to end upon the front edge of the frog, a standard pivotally attached at its lower end to the side of the frog and adjustably connected to the upper end of the frog, a locking key disposed between the front side of the standard and the rear side of the frog, and means at one side of the frog for supporting said key.

6. In a plow, the combination of a frog, a curved point secured upon and extending over the front edge of the frog, means for adjusting the said point along the vertical dimension of the frog, a beam connected 65 with the frog, and means for adjusting the beam relative to the frog to conform to the adjustment of the point.

7. In a plow, the combination of a frog having its front edge forming a regular 70 curve and provided in its front side with a plurality of recesses, and a point consisting of a bar curved from end to end to seat upon the said front curved edge of the frog and having its extremities turned outwardly 75 from said curve, the upper extremity of the point being adapted to engage any one of the recesses in the frog.

8. In a plow, the combination of a frog, a standard adjustably connected to the frog, 80 and a locking key disposed between the frog and standard and provided on its front side with notches adapted to engage the rear edge of the frog and having its rear side curved to fit against the front curved side 85 of the standard.

9. In a plow, the combination of a frog, a standard pivotally attached at its lower end to the frog, interengaging projections on the opposed faces of the standard and the frog, 90 and an adjustable connection between the standard and the frog above the lower end of the standard.

In testimony whereof I affix my signature.

FRANK L. WESTBROOK. [L.S.]
